FABRIC.

No. 18,350.

Patented May 22, 1888.

UNITED STATES PATENT OFFICE.

CHARLES B. SMITH, OF FITCHBURG, MASSACHUSETTS.

DESIGN FOR FABRIC.

SPECIFICATION forming part of Design No. 18,350, dated May 22, 1888.

Application filed April 13, 1888. Serial No. 270,600. Term of patent 3½ years.

To all whom it may concern:

Be it known that I, CHARLES B. SMITH, of Fitchburg, in the county of Worcester and State of Massachusetts, have invented and 5 produced a new and original Design for Fabric, of which the following is a full, clear, and exact description.

My new design is fully illustrated in the accompanying photograph, to which reference 10 is made.

A A represent wide stripes, between which appear the narrow stripes B B. The wide stripes A each show two stripes, a a, separated by a narrow stripe or line, b. The stripes B

each show narrow parallel lines or ribs c, 15 which compose the whole strip, the ribs c being close together.

I claim—

The design for fabric herein shown and described, the same consisting of the stripes A 20 and B B, the stripes A showing the stripes a a and the stripes b between the stripes a a, and the stripes B showing the ribs or lines c, close together, and which compose the stripes B.

CHARLES B. SMITH.
